UNITED STATES PATENT OFFICE.

JOHN B. GLOWACKI, OF CHICAGO, ILLINOIS.

WIRE-SPlicing DEVICE.

Application filed April 24, 1922. Serial No. 556,299.

To all whom it may concern:

Be it known that I, JOHN B. GLOWACKI, a citizen of the Republic of Poland, having declared my intention of becoming a citizen 5 of the United States, and a resident of the city of Chicago, in the county of Cook and State of Illinois, have invented certain new and useful Improvements in a Wire-Splicing Device; and I do hereby declare that the 10 following is a full, clear, and exact description of the same, reference being had to the accompanying drawings, and to the numerals of reference marked thereon, which form a part of this specification.

15 It is an object of this invention to provide a connector which may be quickly and readily applied for uniting wires.

It is a further object of this invention to 20 provide a device which shall take the place of the ordinary twisted junction between electric wires and render the usual junction box unnecessary.

It is a further object of the invention to 25 provide a joint between two electrical wires which shall afford good electrical contact, shall hold the wires firmly against displacement, shall be capable of sustaining a strong pull and shall amply protect the junction against leakage.

30 It is a further object of this invention to provide a joint for electrical contact which shall have a neat and well finished appearance and shall not deteriorate in use either by abrasion of the insulation or by the wires 35 working loose.

It is a further object of this invention to 40 provide a joint for electrical wires which can be applied without the need of any other tools than the usual electrician's pliers.

45 Other and further important objects of this invention will be apparent from the disclosures in the drawings and specification.

The invention (in a preferred form) is 50 illustrated on the drawings and hereinafter more fully described.

On the drawings:

Figure 1 is an external view of the finished joint.

Figure 2 is a longitudinal section thereof.

55 Figure 3 is a view of the joint in the course of preparation.

Figure 4 illustrates a later step in the preparation.

Figure 5 is an end view of the joint.

Figure 6 is a section upon the line 6—6 of Figure 4.

Figure 7 is a longitudinal section upon an enlarged scale.

As shown on the drawings:

The joint is adapted for uniting a heavy 60 wire 1, having a covering 2 of rubber and a woven covering 3 outside thereof, with a smaller wire 4 having a rubber covering 5 and a woven covering 6 outside thereof. It will be obvious, however, from the following description that the joint may be used for uniting other wires and is not limited to the form of wires illustrated. The conductor 4 is illustrated as made up of 65 many small wires twisted together. In the use of the joint in uniting fixture wires to 70 the house wiring, it will frequently happen that one of the two wires to be united is of this character, but the invention is not limited to such cases.

75 The wire 1 is bent upon itself at the joint as indicated at 7 in Figure 7 and the part 8 which is thus bent back lies close beside the wire 1. The wire 4 and the doubled end of the wire 1 are placed inside of a tube 9. 80 When first applied, this tube is cylindrical, but in order to secure the wires therein, the workman pinches the tube so that it is dented or flattened as is shown at 10. He then shifts his pliers and makes a second 85 dent or flattening in a plane at right angles to the first as is shown at 11. Preferably, one of these two dents is in a plane parallel to the plane of the two parallel parts of the wire 1, while the other of these two dents is 90 in a plane at right angles to them. The wire 4 may be introduced into the tube 9 so that it occupies the space at once side of the plane just mentioned and contacts with the part 8 as well as the main body of the wire 1, or 95 it may, as shown in the drawing, be inserted in the same plane as the two parts of the wire 1. The result of the two flattenings at right angles to one another is to compress the twisted wire 4 and to bring it into close 100 contact with the wire 1 and with the tube 9 so that it is very difficult to pull the wires out of the tube 9 after these dents have been made.

105 In stripping the wires to make this joint, the insulation 5 and 6 is removed completely from the end of the wire 4 but the insulation 2 and 3 is not completely removed from the

wire 1. Instead, it is split as is indicated and the split parts are laid back as shown in Figure 3 for the application of the tube 9. In applying, this tube is preferably forced 5 onto the wire 1 until the end of the tube presses against the undivided part of the insulation as shown at 12 in Figure 7. When the tube has been put in place and pinched in the way described, the split portions of 10 the insulation 2 and 3 are laid along the sides of the tube as shown at 13 and 14 in Figure 7.

The joint is covered by a hard rubber casting consisting of a sleeve 15 and a cap 16. 15 The sleeve 15 has a tapering projecting threaded end 17 and the cap has a flaring mouth which is also threaded to co-operate with the threads 17 as shown at 18 in Figures 2 and 7. The threads are easily entered 20 because of the conical shape of the threaded parts. The corners of the sleeve 15 and cap 16 are rounded as shown at 19 to give the finished joint a good appearance. Also the bore of the sleeve and the cap where the 25 wires enter is countersunk or rounded as shown at 20, in order that there shall be no sharp corner to come against the insulation.

In assembling this joint, the insulation is 30 first stripped from the ends of the wires 1 and 4. The end of the wire 1 is then bent upon itself to form a double part 8 and the part of the insulation for the wire 1 which extends from the bend 7 to the end of the 35 bent back part 8 instead of being cut away entirely is only split. The sleeve 15 is slipped over the wire 1 prior to the splitting of the insulation and the cap 16 is slipped over the wire 4 with the mouth of the cap 40 and the conical threaded end of the sleeve toward one another. The sleeve 9 is then passed over the doubled end of the wire 1. The wire 4, if its ends have been frayed, is twisted into a compact shape and passed into 45 the tube 9 beside the doubled wire 1. The tube 9 and the wire 4 are moved toward the wire 1 until the end of the tube abuts against the undisturbed insulation. The tube 9 is then pinched at the points 10 and 11. The 50 insulation 2 and 3 is then placed against the outside of the tube 9 and the sleeve 15 is brought up along the wire 1 until it overlies this replaced insulation. The cap 16 is then brought up along the wire 4 until the 55 threads 18 engage the threads 17.

The cap 16 and sleeve 15 are then rotated relative to one another until the threads are tightly screwed together. For this purpose the sleeve is knurled as shown 60 at 22 and the cap is knurled as shown at 23. During this screwing movement, the inner face of the cap comes against one end of the tube 9 and forces the tube and wires through the sleeve 15 against the undisturbed insulation so that the insulation 2 and 3 is obliged

to make an abrupt turn at the inside of the end wall of the sleeve 15. This insulation makes another abrupt turn where it leaves this inner end wall to proceed over the outer wall of the sleeve 9. Thus there are two 70 abrupt angles in the insulation, two pinched places in the sleeve and the pressing effect of the outer sleeve upon the joint within it, all tending to unite the wires against any pull which might attempt to spread them. 75

I am aware that numerous details of construction may be varied through a wide range without departing from the principles of this invention, and I therefore do not purpose limiting the patent granted otherwise than necessitated by the prior art. 80

I claim as my invention:

1. In a wire splice, an insulated wire having its insulation split axially of the wire, a tube surrounding the wire and having the split ends of the insulation positioned upon the outside of the tube, and means for clamping the split ends of the insulation against said tube. 90

2. In a wire splice, an insulated wire having its insulation split axially of the wire, a tube surrounding the wire and having the split ends of the insulation positioned upon the outside of the tube, and means exterior to the insulation for holding it in contact 95 with the tube.

3. In a wire splice, a wire having its insulation split axially, a second wire spliced to the first wire, means covering said splice and displacing said split insulation away 100 from said first named wire, and means exterior to said insulation holding it in contact with the first named means.

4. In a wire splice, a wire having its insulation split axially, a second wire spliced to the first wire, means covering said splice and displacing said split insulation away from 105 said first named wire, and means exterior to said insulation holding it in contact with the first named means; said two means constraining said insulation into a form having a plurality of abrupt bends. 110

5. In combination, an insulated wire having its insulation split axially, a second wire spliced to said first wire, a covering device 115 in two parts exterior to said insulation surrounding said splice, means for drawing said two parts toward one another, and means actuated by said drawing for forcing said insulation into an angular shape. 120

6. In a wire splice the combination with the skinned overlapping ends of a plurality of insulated wires, of a tube engaged over the overlapping ends of said wires with the insulation of one of said wires engaged 125 over the exterior of said tube, and knurled interfitting insulation members connected to one another to enclose the sleeve and clamp the insulation of said one wire against said sleeve. 130

7. In a wire splice the combination with
the skinned overlapping ends of a pair of
insulated wires, of a tube engaged over the
overlapping ends of said wires with the
5 insulation of one of said wires engaged over
the exterior of said tube, said tube being
pinched to grip the wires in different planes,
knurled members for enclosing the tube, and
a threaded extension on one of said knurled
10 members adapted to be threaded into the

other knurled member to draw said knurled
members together and clamp the insulation
of said one wire against the pinched sleeve.

In testimony whereof I have hereunto sub- 15
scribed my name in the presence of two sub-
scribing witnesses.

JOHN B. GLOWACKI.
